ATTACHMENT BASE FOR A MUSICAL INSTRUMENT SUPPORT STAND

Clifford A. Della-Porta, Rothlet, England, assignor to The Premier Drum Company Limited, London, England, a British company

Filed Jan. 15, 1968, Ser. No. 10,174

Claims priority, application Great Britain July 15, 1967

Term of patent 14 years

Int. Cl. D6—01

U.S. Cl. D33—3

I claim:

The ornamental design for an attachment base for a musical instrument support stand, substantially as shown.
